UNITED STATES PATENT OFFICE.

HARVEY HUBBELL, OF BRIDGEPORT, CONNECTICUT; LOUIE E. HUBBELL EXECUTRIX OF HARVEY HUBBELL, DECEASED.

SIGNAL SYSTEM.

Application filed March 30, 1925. Serial No. 19,295.

- This invention relates to call systems and particularly to what are known as flash light signal systems although it is not necessarily limited to use with visible signals, which is 5 the preferred use, but may also be employed with audible signals. This system is of the type disclosed in my prior application for patent for signal system, Serial No. 684,539, filed January 5, 1924, in which normally open 10 electric circuits run from a convenient central or control station to a number of different local stations whereby an operative at the central station may select any one of a plurality of prearranged signals and transmit 15 it by means of said circuits to the local station or stations for the purpose of signalling the different parties.
- These systems are especially adapted to 20 save time and trouble in large factories, mercantile houses, etc., which comprise a number of different and sometimes widely separated departments and it is frequently necessary to summon from a central station an official or an employee stationed in one of the 25 departments or happening to be in such department when his presence is desired in some other department. In establishments having a private telephone exchange the call system may be conveniently operated by the switch 30 board operator. With this arrangement any one desiring another person may call the operator who in the event the party desired cannot be reached on his own telephone will send out the proper signal to all the departments through this signal system, and then 35 the party required will call the switch board operator from the nearest telephone who will inform him where and by whom he is desired.
- It is an object of the present invention to 40 provide a device of this character which will be more simple in construction than that disclosed in my prior application, but although of simpler construction is capable of transmitting a larger number of different signals.
- It is also an object of this invention to 45 provide a construction and arrangement of signal selecting and operating devices in which the signal operating mechanism, which 50 usually includes a motor, may be placed in any desired location and at some distance from the selective device, if desired, so that any noise incident to the operation of the motor or the make and break mechanism will not annoy the operator at the central station. 55
- It is a further object of the invention to provide a device for performing these functions which will be quick and reliable in operation and not easily gotten out of order, in which any one of a large number of signals 60 may be selected and transmitted quickly and surely with a minimum number of movements or operations required on the part of the operator, in which the signal selected will be automatically continued for any desired length of time, and in which a single movement on the part of the operator will return the device to its original position after the signal has been transmitted, so that it is 65 in readiness for transmitting another signal 70 if desired.
- With the foregoing and other objects in view, I have devised the construction illustrated in the accompanying drawing forming a part of this specification, similar reference 75 characters being employed throughout the various figures to indicate corresponding elements. In these drawings,
- Fig. 1 is a diagrammatical view of the system showing the electrical connections. 80
- Fig. 2 is a top plan view of the selector and control unit with the enclosing casing removed, portions of various elements thereof being broken away to more clearly show the construction and arrangement. 85
- Fig. 3 is a side elevation of the selector and control unit looking from the right of Fig. 2, the enclosing casing being shown in section, and showing the control lever in the on position. 90
- Fig. 4 is a front elevation of the selector and control unit. 95
- Fig. 5 is a side elevation of a portion of the mechanism at the forward end of the selector and control unit showing the control lever in the off position.
- Fig. 6 is a transverse section substantially on line 6-6 of Fig. 3 with the enclosing casing removed. 100
- Fig. 7 is a longitudinal section through the

forward end of the control drum and through the dial, taken substantially on line 7—7 of Fig. 5.

Fig. 8 is an end elevation of the control drum.

Fig. 9 is a side elevation thereof.

Fig. 10 is a development of the control drum.

Fig. 11 is a top plan view of the signal operating or flashing unit.

Fig. 12 is a side elevation thereof looking toward the bottom of Fig. 11.

Fig. 13 is a detail side elevation of one of the make and break devices.

Fig. 14 is an end elevation of the signal control or flasher unit looking from the left of Figs. 11 and 12, and

Fig. 15 is a perspective view of a grouped set of the signals which may be employed at the local stations.

In my prior application above mentioned the signal selector and operating device comprised a single unit which was located at the central station. In my present system the signal operating or flashing mechanism is located in a separate independent unit from the signal selecting and control unit. By this arrangement the signal selecting and control unit only need be located at the central station, while the signal operating or flashing unit may be located at any convenient location desired. There is thus less space required by this system at the central station and as the signal operating or flasher unit may be located any place desired it may be placed in a vault or any other suitable location where any noise incident to the operation of the motor or the make and break mechanism will in no way interfere with or annoy the operator.

The signal selecting and control unit which is located at the central station is illustrated in Figs. 2 to 10 inclusive and comprises a base 1 upon which the various elements of this unit are mounted. Secured to this base is a frame 2 of any suitable material, as cast metal, and preferably of general rectangular shape as shown, which carries the bearings for the various shafts and also carries the other elements of this unit. Extending longitudinally of the frame is a stationary shaft or rod 3 secured at its rear end in a bearing 4 (Fig. 2). Adjacent its forward end a sleeve 5 (Fig. 7) is mounted to turn on this shaft and also in a bearing 6 in the front end of the frame. This sleeve is provided with a laterally extending flange or disc 7 which carries an annular dial 8 of any suitable material secured to the flange or disc 7 by suitable screws 9, and this dial about its inner periphery on its front face carries a scale including radial markings 10 which are numbered in sequence as shown in Fig. 4, and these radial marks of the scale coat with a stationary mark 11 on a stationary disc 12

secured to the front end of the shaft 3 as shown in Fig. 7. This dial and disc are used to select the signals desired in a manner which will later be described. The sleeve 5 on the opposite side of the bearing 6 from the flange 7 carries a disc 13 to which the front end of a cylindrical drum 14 is secured, this disc being mounted to turn with the sleeve 5 by any suitable means as a key 15. A similar disc, not shown, supports the other end of this drum on the shaft 3 and rotates on this shaft as the drum is rotated by means of the dial 8 and the sleeve 5 in the operation of the device as will presently be described.

Above and to one side of the shaft 3 is another shaft 16 (Figs. 2 and 6) which carries a plurality of contact fingers and levers which cooperate with the drum 14 for controlling the functioning of the contact fingers. In the present device there are three sets of these fingers indicated at 17, 18 and 19 (Fig. 1) and the fingers of each set are electrically connected with each other as indicated, although the fingers are spring fingers so that they are movable independently of each other. Each set of fingers is electrically insulated from the other sets of fingers. They are mounted on a support 20 mounted on the shaft 16 and are insulated therefrom and from each other by the insulating plates 21 (Figs. 2 and 6). The levers mentioned above are indicated at 22 (Figs. 2 and 6) and these levers are also mounted on the shaft 16 but between the spring fingers 17, 18 and 19 and the drum 14 as shown in Fig. 6, there being one of these levers for each contact finger. These levers are loose on the shaft 16 but have a projecting lug 23 which may be engaged by shoulder 24 on the support 20 so that under certain conditions this shoulder may engage the lugs on the levers and raise and hold them out of contact with the drum 14. At their opposite ends each lever has an insulating block 25 which under certain conditions engages the under side of the corresponding contact finger and holds it elevated as indicated in Fig. 6, and as will later be described. The levers also carry downwardly projecting pins or studs 26 on their under sides which may either engage the surface of the drum or may pass through openings in this drum to allow the levers to drop as shown in Fig. 6. These openings are indicated at 27 (Figs. 9 and 10) and are arranged in certain order to select the different signals desired as will later be described.

Mounted at one side of this drum 14 is an upright panel 28 of suitable insulating material such as bakelite, which panel is secured to the frame by any suitable means such as screws 29, and on the inner wall of this panel are mounted a plurality of spaced upright bars 30 having inwardly and downwardly turned upper ends 31 forming stationary contacts which may be engaged by the contact fingers 17, 18 and 19, there being one of these

bars 30 for each contact finger. The bars are secured to the panel by screws 32. On the opposite side of the panel are mounted a series of longitudinally extending bus bars 33 and it will be noted that in the present instance each bus bar is electrically connected to three of the bars 30 by means of the connections 34 at their opposite ends and at their centers, these connections passing through the panel. It will be apparent from Figs. 1, 2 and 3 that the bars 30 are arranged in three sets to correspond with the three sets of contact fingers 17, 18 and 19, and that each bus bar 33 is electrically connected to the corresponding bar 30 of each set. Thus the upper bus bar 33^U is connected to the bars 30 which correspond with the contact fingers 17^U, 18^U and 19^U. In the same way the second bar 33^W is electrically connected with the bars 30 corresponding with the contact fingers 17^W, 18^W and 19^W, and so on through the entire series. The bars 30^x corresponding to the first contact fingers 17^x, 18^x, and 19^x of each set are not connected to any of the bus bars 33 but are connected by leads 35, 36 and 37 to the spring contacts 38, 39 and 40 respectively in the signal operating or flasher unit as shown in Fig. 1.

In the present system each local station comprises a set of six lamps 41 of different colors, in the present case white (W), green (G), yellow (Y), blue (B), red (R), and pink (P), although, of course, any other colors may be employed as desired, but each lamp should be a different color from each of the other lamps. The lamps are also numbered as indicated in Fig. 15 so that in case a party is color-blind the signals may be recognized from the numbering of the lamps. In other words the lamps are given different means of identification and the preferred means of identification are the different colors for the lamps, or the numbering, or both. One side of each lamp is connected to one side 42 of a circuit from any suitable source of power and the other side of each lamp is connected by a lead 43^W, 43^G, etc., to the corresponding bus bars 33^W, 33^G, etc., and through these bus bars to the stationary contacts 30^W, 30^G, etc., as shown in Fig. 1. The other side 44 leading from the source of power is connected to a brush contact 45 in the flasher or make and break device, and this supply circuit is controlled by a switch 46, preferably a suitable type of snap switch. This switch is located in and comprises a part of the signal selector and control unit and is indicated in Figs. 2 and 5.

The selector and control unit also comprises means for manipulating the contact fingers 17, 18 and 19 and the switch 46. In the forward portion of the frame 2 is a transverse rod 47 upon which a control lever 48 is mounted, this lever being secured to the rod by any suitable means as a pin 49. Also secured to the rod is a crank 50 by any suitable means as

a pin 51, and a cam 52 is secured to the rod by a pin 53. The sleeves 54 and 55 respectively of this crank and cam project beyond the ends of the rod 47 and receive bearing studs 56 which are threaded in the sides of the frame, as shown in Fig. 6. By this arrangement the rod with the lever, crank and cam may turn together on these bearing studs. Similarly mounted slightly to the rear of the rod 47 is another rod 57 upon which is secured a crank arm 58 as by means of a pin 59, and a switch operating crank arm 60 is secured to the rod by a pin 61. Between the sleeves 62 and 63 for these two elements is an arm 64 which is loosely mounted on this rod and so may turn independently thereof. This arm carries a pin or stud 65 adjacent its free end, which stud is tapered or V-shaped at its upper end, as shown at 66, to seat in notches 67 in the rim of a circular plate or disc 68 (Figs. 5, 6 and 7) carried by the front end 13 of the drum 14, this disc being mounted on the drum by any suitable means, such as rivets 69. The lower end of the pin or stud 65 is arranged to cooperate with a cam element 70 secured to the control lever 48 so that in certain positions of this lever the cam will lift the arm 64 and the pin 65 and hold its upper end in a notch 67 to lock the drum against rotary movement.

The cam element 52 has an inclined cam surface 71 (Fig. 2) and a straight surface 72 leading therefrom which is in a plane at substantially right angles to the axis of the rod 47 on which the cam swings, and a roller 73 mounted on the lower end of an arm 74 runs on the surfaces to swing the arm and the block or rocker support 20 on the shaft 16, which block or support carries the spring contact fingers 16, 17 and 18. A spring 75 secured to this support 20 engages one side of the frame and tends to swing this support in the opposite direction or counter-clockwise, as viewed in Fig. 6, and retains the roller 73 against the cam surfaces.

The crank member 50 (Fig. 5) is provided with a notch 76, one side of which as shown at 77, is longer than the other side so that it projects above the curved surface 78 preferably formed on the arc of a circle with the axis of the rod 47 at its center. The crank arm 58 carries a roller 79 which is so positioned as to run on the curved surface 78 and may also, as shown in Fig. 3, seat in the notch 76. The arm 58 has a projection 80 beyond the roller 79 which will engage the sleeve 54, as shown in Fig. 3, and limit the movement of the arm 58 and also the control lever 48. The crank arm 60 is connected by link 81 to the switch arm 82 so that as the arm 58 and crank 60 are swung about their pivots the switch arm 82 will be operated to open and close the switch 46 in a manner presently to be described.

Referring to Figs. 1 and 11 to 14 it will be noted that the signal operating or make and

break unit comprises a base 83 upon which the elements of this unit are mounted. The spring contacts 38, 39 and 40 and the brush contact 25 are mounted on a block 84 and are 5 insulated therefrom and from each other by the insulation 85. The spring contacts 38, 39 and 40 are of the type illustrated in my prior application above mentioned and specifically claimed in my application, Serial No. 19,294 10 filed March 30, 1925, which is a division of the above mentioned application. As indicated they comprise a bar 86 rigidly attached to and insulated from the supporting block and to which the leads 35, 36 and 37 are connected by 15 binding screws 87. At their opposite ends are a pair of leaf springs 88 and 89 secured on the upper and lower side of the bar respectively by any suitable means, as rivets 90. Secured to the free end of the upper leaf 20 spring is a contact plate or block 91, it being secured to the spring by a screw 92, and to give a more rigid connection and to prevent the contact turning about the screw it is preferably provided with a transverse groove in 25 its upper surface into which the down turned end 93 of the spring is seated. The lower leaf spring 89 engages the under side of the contact block 91, as shown in Fig. 12, and tends to lift this block against the action of 30 the upper spring 88, this upper spring tending to force the block downwardly. They are so adjusted that when the contact 91 is otherwise unsupported the springs neutralize each other with the contact substantially in the 35 position shown in Fig. 12 and in dotted lines shown in Fig. 13. The contact plates or blocks 91 are mounted in the paths of movement of substantially L-shaped contacts 94, 95 and 96 which are mounted on a rotatable 40 sleeve 97 carried by the shaft 98, this sleeve being insulated from the shaft by an insulating sleeve 99. As the contacts 91 run off the contacts 94, 95 and 96 under action of the upper spring 88 their movement is arrested by 45 the lower springs 89 which therefore form a spring bumper or yielding arresting means so that there is practically no noise. The shaft 98 is mounted in suitable bearings 100 carried by the frame and carries a worm 50 gear 101 meshing with a worm 102 on a shaft 103 operated by the electric motor 104. As will be seen from Fig. 1 the motor is connected across the line 42—44 by the conductors 105 and 106 so that it is controlled by the switch 46. The brush contact 45 connected to the 55 lead 44 is a spring contact bearing continuously on the ring 107 carried by the sleeve 97 so that this ring has electrical connection with the contacts 94, 95 and 96. As the signal operating unit comprising the motor and the make and break elements is a separate and distinct unit from the selector and control unit, the leads 35, 36, 37, 44, 104 and 105 connecting them are mounted in a cable, not 60 shown, which passes through the openings 65

109 in the fixture 108 secured to the frame 2. The binding posts 110^w, 110^c, etc., for the leads 43^w, 43^c, etc., for connecting these leads to the bus bars 33^w, 33^c, etc., are mounted on an insulating block 111 (Fig. 3). For convenience in making connections binding posts 112 are mounted on the panel 28 to which the leads 113 form a suitable source of power are connected. From these posts leads extend to the switch 46, back to the binding post 114 and 70 from these posts the wires 104 and 44 lead to the motor and brush 45 in the make and break unit. The leads 35, 36 and 37 are connected to the bars 30* through the binding post 115. 75

The operation is as follows: When the 80 system is not operating to transmit a signal the elements are in the position shown in Fig. 5, that is, the control lever 48 is swung backwardly under the base 1, the pin or stud 65 is removed from the notches 67 leaving 85 the drum 14 free to rotate, the arm 74 is swung to the right from the position shown in Fig. 6 under the action of spring 75 so that the shoulder 24 on the support 20 engages the lugs 23 on the levers 22 and holds 90 these levers elevated with the pins or studs 26 out of engagement with the drum 14 and the insulating blocks 25 on the levers 22 will hold the contact fingers 17, 18 and 19 out of 95 engagement with the stationary contact 30. 100 The circuits through these contacts are thus all open. Furthermore, the roller 79 (Fig. 5) is resting on the curved surface 78 so that the lever arm 60 is swung to the right, as viewed in Fig. 5, and the main control switch 105 46 is open. Thus the motor and the make and break device operated thereby is stationary and not operating.

If the operator now wishes to flash a given 110 signal at the local stations comprising the colored and numbered lamps 41, she rotates the dial 8 to bring the desired number and its radial line 10 opposite the stationary mark 11. This will rotate the drum 14 to bring the proper opening or openings 27 in the 115 drum under the pins or studs 26 on the proper lever or levers 22. She then pulls forwardly on the control lever 48 swinging it to the left or clockwise, as viewed in Fig. 5, to the position shown in Fig. 3. This movement of the 120 lever will first lock the drum 14 against movement by raising the pin or stud 65 so that its upper V-shaped end will seat in one of the notches 67 in the edge of the plate 68, as shown in Fig. 6. This locks the drum in proper position. The upward movement of the pin 65 is caused by the lower end of this pin riding up on the cam 70. After the pin has once 125 been raised so that it is seated in one of the notches 67 it is retained therein by the surface 70, and as this surface is concentric with the shaft 47 any further movement of the lever will not affect the stud 65. Immediately after the drum 14 is locked as just described the roller 73 (Figs. 2 and 6) rides up on the 130

inclined surface 71 (Fig. 2) and swings the arm 74 (Fig. 6) outwardly or clockwise as view in this figure. This swings the supporting block 20 on the shaft 16 in the same direction and moves the shoulder 24 upwardly. This allows the levers 22 to drop downwardly so that the lower end of the pins or studs 26 will rest on the surface of the drum 14 if no openings 27 are in alignment therewith and will, therefore, hold the spring contact fingers 17, 18 and 19 elevated and out of contact with the stationary contact bar 6, these fingers being supported by the insulating blocks 25 carried by the levers. If, however, an opening 27 is in alignment with any of the pins or studs 26 this pin will pass through the opening as indicated in Fig. 6, and will allow the corresponding lever 22 to drop as shown. This will remove the support from under the corresponding contact finger 17, 18 or 19 and will allow this finger to engage the upper end 31 of the corresponding stationary contact 30 as also indicated in Fig. 6. This will close the circuit to the corresponding lamp 41 as will be apparent from Fig. 1. There are no levers 22 under the contact fingers 17*, 18* and 19* so that on every operation of the lever 48 these contact fingers 17*, 18* and 19* engage the corresponding stationary contacts 30*, connected to the leads 35, 36 and 37 leading from the contacts 38, 39 and 40 of the make and break device. This arrangement is preferred for structural and operative reasons but, of course, the leads 35, 36 and 37 may be connected directly to sets of contact fingers 17, 18 and 19. After the roller 73 has swung the support 20 as just described this roller rides along the straight surface 72 (Fig. 2) and retains the block 20 in this position with the selected contact fingers 17, 18 or 19 engaging the stationary contacts 30.

Further movement of the lever 48 will cause the roller 79 (Figs. 3 and 5) to run off the curved surface 78 and into the notch 76, the longer side 77 of this notch engaging this roller and forcing it down into the notch to the position shown in Fig. 3. This will swing the lever arms 58 and 60 to the left or counter-clockwise, as viewed in Figs. 3 and 5, and move them to the position shown in Figs. 2 and 3. This movement will swing the switch arm 82 to the left from the position shown in Fig. 5 to the on position shown in Fig. 2 and will close the circuit from the source of current supply. The motor 104 will then immediately start to rotate and through the drive 101—102 will rotate the contacts 94, 95 and 96. It will be apparent that as these contacts rotate they will engage the contact blocks 91 of the spring contacts 38, 39 and 40 and will thus close the circuit through these contacts because they are in electrical connection with the lead 44 through the brush 45 and ring 107. Thus any contact finger 17, 18 and 19 which happens to be in contact with the stationary contact 30 will complete the circuit from the corresponding contact 38, 39 or 40 to its particular lamp located at the local stations. It will be noted from an inspection of Figs. 1, 11 and 12 that there are two contacts 95 to engage the central contact 39 so that there will be two engagements with this member 39 for each revolution of the flasher shaft 98, while there is only one contact 94 and one contact 96 to engage the contacts 40 and 38 respectively, so that the circuit is closed through these contacts only once for each revolution of the shaft 98. The contacts 95 are spaced from each other a third of a revolution or one hundred and twenty degrees while the contacts 94 and 96 are located on diametrically opposite sides of the shaft, and the contact 96 is half way between the two contacts 95.

This arrangement is used to secure various combinations of lamp flashes to give various signals, and by this arrangement of contacts signals may be given which comprise one flash only of any given light for one revolution of the shaft 98. In other words the signal will be a continuous slow flashing of this one light, the flashes having equal time intervals between them. Or there may be three flashes of a signal light for each rotation of the shaft 98 at equal intervals giving a rapid and continuous flash of the light three times as fast as the single flash first mentioned. Or further there may be two rapid flashes of the single light with an interval twice as long between them, or there may be a single flash of any one light combined with a double flash of another light for each revolution of the shaft 98. For example, as shown in Fig. 10, there are three sets of openings 27 in the drum 14. The first set of openings is in the left third portion of the drum being shown in the space 19^P, these openings coacting with the levers 22 for the forward or left set of contact fingers 19. The openings in the central portion 18^P of the drum cooperate with the levers 22 under the contact fingers 18, while the right hand portion 17^P of the drum cooperates with the levers 22 under the fingers 17. For example, supposing the operator wishes to flash the signal corresponding to No. 1, which may be determined from any suitable chart, she sets the dial 8 with the line 1 opposite the stationary line 11. This will bring the opening 27 at the lower left hand corner of Fig. 10 on the horizontal line 1 under the pin 26 carried by the lever 22 under the finger 19^W. Now when the control lever 48 is drawn forwardly this lever will drop allowing the finger 19^W to engage its stationary contact 30. All the other fingers except the fingers 17*, 18* and 19* will be retained out of engagement with their stationary contact 30 as there are no other openings in the drum on the line 1 as will be apparent from an in-

spection of Fig. 10. Therefore, as the make and break or flasher shaft 98 rotates the circuit will be closed through the white light (W) once for each revolution of the shaft 98 because the contact 40 (Fig. 1) engages the contact 94 once for each revolution. Thus we have a slow continuous flashing of the light (W). The circuit is completed from the switch 46 through lead 44 to brush 45, ring 107, sleeve 97, contact 94, spring contact 40, lead 37 to the left hand or forward stationary contact 30^x, finger 19^x, finger 19^w, to the forward stationary contact 30^w, bus bar 33^w, lead 43^w, lamp (W) and back through the wire 43 to the switch 46 and out on the line. If now the dial is turned to bring line 2 opposite the mark 11 an opening 27 in the central panel of the drum on the line 2 of Fig. 10 will be brought under the lever 22 under the contact finger 18^w. Then manipulation of the control lever 48 will allow this finger 18^w to drop as there are no other openings on this line 2, the circuit to the lamp (W) will be closed twice for every revolution of the shaft 98 by means of contacts 95, and there will be a double flash of the white light with a short interval between the single flashes and a long interval between the double flashes. If now the drum is turned to the third position with line 3 opposite the mark 11, the elongated opening 27 (Fig. 10) at the left lower end of the panel 19^p and the opening 27 in the lower end of the panel 18^p are on the line 3. Thus when the control lever 48 is operated the contact fingers 19^w and 18^w will be allowed to drop to engage their stationary contacts 30. We will then have three flashes of the white light for each revolution of the shaft 98, one from the contact 94 and two from the contact 95, and there will be a rapid flashing of the white light with equal intervals between them. If now we turn the drum to bring line 4 in alignment with the mark 11 we will have the elongated opening 27 at the lower left hand corner of the panel 19^p under the lever 22 of the finger 19^w and we will have the opening 27^a in the central panel 18^p under the lever 22 for the finger 18^a. Thus when the lever 48 is operated there will be a single flash of the white light and two flashes of the green light for each revolution of the shaft 98, the white light being flashed by the contact 94 and the green light by the contacts 95. The same system is carried throughout the entire drum giving a signal which may comprise any light or a combination of that light with any other light. If we move the drum to the position 9 (Fig. 10), that is, to bring the line 9 on the dial opposite the mark 11, it will be seen that the elongated opening 27 in the panel 19^p at the lower end thereof is on the line 9 and there is also an opening 27^a in the panel 17^p on this line. Therefore, when the lever 48 is operated the contact fingers 19^w and 17^a will be allowed to drop to engage

their corresponding stationary contacts 30. There will thus be for each revolution of the shaft 98 one flash of the white light through the contact 24 and one flash of the green light through the contact 96, and these flashes will be equally spaced.

It is to be noted that for each setting of the selector and control device, and after the lever 48 is swung to the on position shown in Fig. 3, the signal selected will be flashed automatically and continuously, that is, will be continuously repeated until the lever 48 is swung back to its original position shown in Fig. 5. As this lever is swung back the first operation is to swing the switch arm 82 to the off position which stops the motor and disconnects the whole device from the source of power. The next operation is to swing the contact fingers 17, 18 and 19 which may have been allowed to drop upwardly away from engagement with the stationary contacts 30. This is caused by the roller 73 (Figs. 2 and 6) running down the incline 71 (Fig. 2) and allowing the spring 75 to swing the support 20 for these fingers counter-clockwise, as viewed in Fig. 6. It is to be noted that as the current is shut off from the contact fingers 17, 18 and 19 and the stationary contacts 30 before these fingers are raised there is no arcing between these contacts so that they do not become corroded or injured. The next and last operation as the lever 48 swings backwardly to allow the pin or stud 65 to move downwardly out of engagement with the disc 68 and unlock the drum 14 so that it may be set for any other signal. It is also to be noted that as the signal operating or make and break device is a separate unit from the selecting and control unit, this make and break unit with its motor may be placed in any position desired and is not necessarily located at the central station. It may, therefore, be placed in a vault or any other position where the noise of the motor or the noise of the make and break contacts will annoy no one.

It will also be apparent from the foregoing description that by arranging the contacts as shown I can secure a large number of different signals with a comparatively simple mechanism which occupies a very small space, and that any one of these large number of signals may be easily and quickly selected and transmitted to the local stations for any desired period by a simple manipulation of the dial 8 and the arm 48. In the layout shown sixty different signals may be transmitted to the local stations.

Having thus set forth the nature of my invention, what I claim is:

1. A signaling system comprising a plurality of electric circuits, a grouped set of signal lights having different means of identification arranged with a light in each circuit, a selective device comprising a group

- of stationary contacts including a contact for each circuit, a plurality of electrically connected, independently movable fingers adapted to engage the stationary contacts, a selective means for moving certain of said fingers into engagement with corresponding stationary contacts and retaining them in this position, a make and break device electrically connected with said fingers and operable independently thereof, and means for operating the make and break device.
2. A signaling system comprising a plurality of electric circuits, a grouped set of signal lights having different means of identification arranged with a light in each circuit, a selective device having a group of stationary contacts including a contact for each circuit, a plurality of electrically connected independently movable fingers adapted to engage the stationary contacts, a rotary drum, means coacting with the drum to allow certain of the fingers to engage the stationary contacts and to hold the remaining fingers out of engagement with the contacts, a make and break device electrically connected with the fingers, and means for operating the make and break device.
3. A signaling system comprising a plurality of electric circuits, a grouped set of signal lights having different means of identification arranged with a light in each circuit, a selective device comprising a group of stationary contacts including a contact for each circuit, a plurality of electrically connected, independently movable fingers adapted to engage the stationary contacts, a selective means for moving certain of said fingers into engagement with corresponding stationary contacts, a make and break device electrically connected with said fingers, means for operating the make and break device, and means controlled by the selective device for controlling the said operating means.
4. A signaling system comprising a plurality of electric circuits, a grouped set of signal lights having different means of identification arranged with a light in each circuit, a selective device having a group of stationary contacts including a contact for each circuit, a plurality of electrically connected independently movable fingers adapted to engage the stationary contacts, a rotary drum having a plurality of openings, a plurality of pivoted levers located between the fingers and the drum and provided with studs to engage the surface of the drum and project into the openings when they are in alignment with the studs, a pivoted rocker upon which the fingers are mounted, said rocker being provided with means to move the levers away from the drum, a make and break device electrically connected with the fingers, means for operating the make and break device, and means for swinging said rocker to move the fingers toward and from the contacts.
5. A signaling system comprising a plurality of electric circuits, a grouped set of signal lights having different means of identification arranged with a light in each circuit, a selective device comprising a unit adapted to be set to select for operation any one of said signals, a separate independent unit including a make and break device electrically connected with the first unit for automatically and continuously operating the signal selected and means for operating said make and break device, and means in the first unit controlled by the selective device and electrically connected with the make and break device for controlling the same.
6. A signaling system comprising a plurality of electric circuits, a grouped set of signal lights having different means of identification arranged with a light in each circuit, a selective device comprising a unit adapted to be set to select for operation any one of said signals, a separate independent unit including a make and break device electrically connected with the first unit for operating the signal selected and an electric motor for operating said make and break device, a switch in the first unit electrically connected with the motor for controlling it, and means connected with the selective device for operating the switch.
7. A signaling system comprising a plurality of electric circuits, a grouped set of signal lights having different means of identification arranged with a light in each circuit, a selective device comprising a unit adapted to be set to select for operation any one of said signals, a separate independent unit electrically connected with the first unit for automatically and continuously repeating the signal selected by said device, and means in the first unit controlled by said setting operation for controlling the operation of the second unit.
8. A signaling system comprising a plurality of electric circuits, a grouped set of signal lights having different means of identification arranged with a light in each circuit, a selective device comprising a unit adapted to be set to select for operation any one of said signals and also a combination of any signal with any other signal, a separate independent unit electrically connected with the first unit for operating the signal or signals selected, and means in the first unit controlled by said setting operation for controlling the operation of the second unit.
9. A signaling system comprising a plurality of electric circuits, a grouped set of signal lights having different means of identification arranged with a light in each circuit, a selective device comprising a rotary drum, contacts in said circuits, independently mov-

- able contacts adapted to coat with the first contacts to control said circuit, means cooperating with the drum for determining the positions of the movable contacts, a graduated dial connected to the front end of the drum for setting the same, means for operating said movable contacts including a pivoted lever mounted to swing in a plane substantially parallel with the axis of the drum, and means for operating the signal selected. 10
10. A signaling system comprising a plurality of electric circuits, a grouped set of signal lights having different means of identification arranged with a light in each circuit, a selective device comprising a rotary drum, a panel at one side of the drum, a plurality of sets of contacts carried by said panel, means for connecting each light to a contact in each set, a plurality of sets of electrically connected independently movable contacts each adapted to engage a corresponding contact in the first mentioned sets of contacts, means coacting with the drum for controlling the engagement of the movable contacts with the other contacts, a rotating element, a plurality of separate contacts carried by said element, electrical conducting means arranged to engage the latter contacts intermittently as the element is rotated, means for connecting the electrical conducting means with the sets of movable contacts, and means for operating the rotating element. 25
11. A signaling system comprising a plurality of electric circuits, a grouped set of signal lights having different means of identification arranged with a light in each circuit, a selective device comprising a rotary drum, a panel at one side of the drum, a plurality of sets of upright contacts carried by said panel, a plurality of horizontal bars each connected to a contact in each set, means for connecting each lamp to one of said bars, a plurality of sets of electrically connected independently movable contacts each adapted to engage a corresponding upright contact, means coacting with the drum for controlling the engagement of the movable contacts with the upright contacts, and a make and break device electrically connected with the sets of movable contacts. 45
12. In a signaling system, a plurality of electric circuits, a grouped set of signal lights having different means of identification arranged with a light in each circuit, a plurality of sets of stationary contacts the number of contacts in each set being one greater than the number of lights, means for connecting each light circuit to one of the contacts in each set, make and break contacts connected to the remaining contacts of each set, a rotating element, contacts carried by said element to engage the make and break contacts as the element rotates, a plurality of sets of movable contact fingers, there being a finger to engage each of the first mentioned contacts and the fingers of each set being electrically connected, and selective means for moving certain of said fingers into engagement with the stationary contacts and to retain the others out of engagement therewith. 65
13. In a signaling system, a plurality of electric circuits, a grouped set of signal lights having different means of identification arranged with a light in each circuit, a plurality of stationary contacts in said circuits, a plurality of independently movable contact fingers adapted to engage the stationary contacts, a plurality of levers under the contact fingers having downwardly projecting pins, a rotary drum having openings adapted to be brought into alignment with said pins, means for causing movement of the fingers and levers toward and from said contacts and drum respectively, a circuit make and break device connected with said fingers, and means for operating the make and break device. 75
14. In a signaling system, a plurality of electric circuits, a grouped set of signal lights having different means of identification arranged with a light in each circuit, a pair of sets of stationary contacts, there being a contact in each set in each circuit, a pair of sets of independently movable contact fingers arranged to engage the stationary contacts, the fingers in each set being electrically connected, a selective means for controlling the engagement of the fingers with the stationary contacts, a pair of brush contacts electrically connected respectively to the sets of contact fingers, a rotary element, contacts carried by said element arranged to engage one of the brush contacts and spaced about said element approximately sixty degrees, a third contact on said element adapted to engage the other brush contact and located approximately sixty degrees from the other contacts on said element, and means for rotating said element. 90
15. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 100
16. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 105
17. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 110
18. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 115
19. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 120
20. In a signaling system, a plurality of electric circuits, a grouped set of signal lights having different means of identification arranged with a light in each circuit, three sets of stationary contacts, each circuit being connected to a contact in each set, three sets of contact fingers independently movable toward and from the stationary contacts, the fingers of each set being electrically connected, a selective device for controlling the engagement of the individual fingers with the stationary contacts, three brush contacts connected one to each set of fingers, a rotary element, a pair of contacts carried by said element arranged to engage one of the brush contacts, a pair of diametrically oppositely disposed contacts on said element arranged one to engage each of the other brush contacts respectively, said latter contacts being angularly disposed. 125

larly disposed on the rotary element intermediate the first pair of contacts, and means for rotating said element.

16. In a signaling system, a plurality of 5 electric circuits, a grouped set of signal lights having different means of identification arranged with a light in each circuit, a selective device arranged to select for operation any one of said circuits including a rotary 10 drum, means cooperating with the drum for selecting the circuit or circuits desired, a disc secured to the drum having notches in its periphery, a pivoted lever, a tapered pin carried by said lever arranged to seat in said notches, a control lever, a cam connected to 15 the control lever for shifting said pin to lock the drum, a circuit make and break device connected to said circuits through said selective device, a motor for operating the make and break device, a switch for controlling 20 the motor, a pivoted lever connected to the switch, a roller carried thereby, and a cam with a notch at one end connected to the operating lever which is engaged by said roller whereby the lever is operated. 25

In testimony whereof I affix my signature.

HARVEY HUBBELL.
